UNITED STATES PATENT OFFICE.

LAWRENCE WESLEY HORNE AND WARREN NOBLE CRANE, OF NEW YORK, N. Y.

ELECTRICALLY-OPERATED SPEED-CONTROLLING DEVICE FOR TRAINS.

1,212,224.

Specification of Letters Patent. Patented Jan. 16, 1917.

Application filed August 5, 1913. Serial No. 783,039.

To all whom it may concern:

Be it known that we, LAWRENCE WESLEY HORNE and WARREN NOBLE CRANE, citizens of the United States, residing, respectively, at New York city, in the county of Kings and State of New York, and at New York city, in the county of Bronx and State of New York, have invented a new and useful Improvement in Electrically - Operated Speed-Controlling Devices for Trains, of which the following is a specification.

This invention relates to electrically operated speed controlling devices for trains, and our improvements have particular reference to automatically functioning means whereby the brakes are applied when a train passes a signal set at "danger" at greater than a predetermined rate of speed. But when the speed of travel of the train is below that predetermined rate then our control device will not operate to cause the brakes to be applied.

In brief it is the purpose of this device to correct the neglect of the engineer in omitting to slacken speed when approaching a danger signal, but to not interfere with the engineer's control of his train if he is properly observing the signal indications.

In the drawing: Figure 1 is a partially diagrammatic, and partially sectional elevation of our improved apparatus, as applied to a locomotive, and in conjunction with track contact members. Fig. 2 is an end view, in part, of the same; and Fig. 3 is a top plan view of one of the track contact devices.

The equipment in our control device includes the track contact members *a* and *b*, which may be placed beside the rail, in parallel planes, one in advance of the other. The distance which separates members *a* and *b* is determined by the speed at which a train is permitted to travel between said members. The member *a*, is composed of separated sections *a'*, bonded in a particular manner as shown in Fig. 3. These contact members are bonded by relay disks *c*. Brushes *d* *e*, included in local circuits *f* *g*, respectively, and carried by a train, are adapted to traverse the contact members *a'* and to be connected thereby whenever said contact members are themselves connected through the agency of relay disks *c*. A rearward brush, *h* is out of alinement with contacts *a'*, and is held normally elevated out of passing contact with member *b* by a spring

i in dashpot *j*, and is further adapted to be forced downwardly for the purpose of making contact with member *b* by air pressure from the main reservoir, entering 60 through a magnetically operated valve *k*. Brush *h* has a supporting stem *h'* carrying a piston *h''* in dashpot *j* and said stem *h'* also carries a relay disk *h'''* for a purpose to be described hereinafter. A magnetically 65 operated valve *l*, included in the circuit *f*, controls the pressure from the brake pipe.

Where this device is used there need be no track appliances projecting above the top of the rail. The track devices employed are 70 located in pairs in the manner shown in the drawings, the first device as *a*, encountered by a train operating in the normal direction of traffic is composed of contact segments, normally free of connection with 75 each other. When the preceding block is occupied the track relay *c* is deenergized by the usual bridging of an insulated rail section by the wheels of the train occupying that block. The dropping of the relay disks 80 *c*, connects the contact segments, so that brushes *d* *e*, carried by the locomotive of an approaching train, may be thereby electrically connected together.

The contact members *a'* are bonded in a 85 manner to cause the brushes *d* and *e* to short circuit the battery *g'* when the disks *c* have been dropped by an interruption of the track circuit. The arrangement is such that there are always two sections between a pair 90 of bonded members, those two sections also having their own similar bonding arrangement. The brushes *d* and *e* are normally held at rail level and their location on the locomotive is so arranged that they cannot 95 both touch any one contact segment at the same time, neither can they be electrically connected by crossovers, turpouts, or any "spécial work." The additional contact brush *h* is normally held clear by dashpot 100 *i*. Therefore if a block section approached is clear, brushes *d* and *e* cannot be connected and brush *h* remains in position shown. When the preceding block section is occupied, brushes *d* and *e* are connected by track devices *a'* and battery *g'* is short circuited and the magnet valve *k* is deenergized, opening the valve and admitting main reservoir pressure to the dashpot, causing spring *i* to be compressed, thereby dropping brush *h* to operative position. At the operative position a contact disk *h'''*, carried

by the dashpot piston rod h' causes the energizing of magnet valve k , which shuts off main reservoir pressure from the dashpot. The return of brush h to normal position is 5 performed by permitting air pressure to gradually exhaust from the dashpot to atmosphere as through dashpot orifice h^4 , the entire operation affording a method of maintaining brush h in its operative position 10 for a definite predetermined period in conformity with a predetermined train velocity permitted in approaching the second track device b .

When the train speed be within the 15 proper limits, brush h will have moved "clear" and therefore will not make contact on the second track device b , and no application of the train brakes occurs.

If the engineer does not properly control 20 his train at any point at, or beyond, the distance signal, he will not consume sufficient time to permit brush h to move "clear" and brushes h and d are then connected by track device b . Device b may simply be 25 constructed of a plain rail section, and it is placed in alinement with brush h , whereas the first track device a is in alinement with brush e , brush d having sufficient width to make contact with both track devices. The connecting of brushes h and d 30 short circuits battery g^2 and deenergizes magnet valve l , causing the train brakes to be applied.

The device may be so designed that the 35 brakes may only remain applied until brush h has returned to normal position. In normal position relay disk h^3 will bridge the contacts h' again, reestablishing the circuit and permitting the release of the brakes.

40 We claim:

1. A valve, an electrical circuit, and a source of electrical supply for said valve and brushes included in said electrical circuit, a second valve, an electrical circuit and 45 a source of electric supply for said valve, and brushes included in said electrical circuit, means operated by said first mentioned valve for moving one of said brushes into the plane of the other said brushes, means 50 for short circuiting the source of supply for said first mentioned valve to obtain said movement of said movable brush and means for short circuiting said movable brush with another said brush for operating said second valve.

2. A device having a plurality of independent electrical circuits, a magnetically

operated valve arranged in each said circuit, means for short circuiting one said valve to obtain an operation thereof, and 60 means operated by said valve for short circuiting the other said valve to obtain an operation thereof.

3. An electrical speed controlling device comprising a plurality of brushes, a source 65 of electric current supply for said brushes, an electric circuit in which each said brush is included, sectional track contact devices adapted to be bonded together as desired and to be engaged by said brushes, another 70 and movable brush, a pressure operated rod secured to said brush for holding it normally away from the plane of contact, an electrically operated valve in said first mentioned circuit for controlling the pressure 75 for said rod, and means for urging the return of said movable brush and an electrically operated relief valve arranged in a train line air pipe and means operated by said movable brush and one said first mentioned brush for opening the circuit through said relief valve as herein specified.

4. An electrical speed controlling device comprising a plurality of metallic brushes, electric circuits in which said brushes are 80 included, a track contact device composed of a plurality of separated sections, in the path of certain of said brushes, an electrical circuit adjacent to said sections, a solenoid in said circuit and adapted to electrically 85 connect alternate contact sections and certain of said brushes by the interruption of the electrical circuit through said solenoid as and for the purpose set forth.

5. A device having two batteries, three 90 brushes electrically connected to said batteries, a pressure release valve in the electrical circuit of one said battery, means for moving one said brush, an electrically operated valve in another said electrical circuit and adapted to control the movement of said movable brush, means adjacent to a track and operable upon said brushes for short circuiting one said battery to operate 95 said controlling valve, said means being 100 adapted to close the circuit between one of said first mentioned brushes and the movable brush to operate said releasing valve.

LAWRENCE WESLEY HORNE.
